(57) **CLAIM**

We claim the ornamental design for the laptop support ramp, as shown and described.

DESCRIPTION

FIG. 1 is a perspective view of a laptop support ramp showing our new design;

FIG. 2 is a side view thereof, the other side being a mirror image of FIG. 2;

FIG. 3 is a front view thereof;

FIG. 4 is a rear view thereof;

FIG. 5 is top view thereof;

FIG. 6 is a bottom view thereof; and,

FIG. 7 is a perspective view thereof in use as a laptop support ramp with the broken line showing environmental association matter for illustrative purposes only and forming no part of the claimed design.
